DESIGN.

—o—
L. K. FULLER.
ORGAN CASE.

No. 20,419.

Patented Dec. 23, 1890.

UNITED STATES PATENT OFFICE.

LEVI K. FULLER, OF BRATTLEBOROUGH, VERMONT, ASSIGNOR TO THE
ESTEY ORGAN COMPANY, OF SAME PLACE.

DESIGN FOR AN ORGAN-CASE.

SPECIFICATION forming part of Design No. 20,419, dated December 23, 1890.

Application filed July 14, 1890. Serial No. 358,749. Term of patent 7 years.

To all whom it may concern:

Be it known that I, LEVI K. FULLER, of Brattleborough, in the county of Windham and State of Vermont, have invented and produced a new and original Design for an Organ-Case, of which the following is a specification.

This design relates to the ornamentation of the cases of organs, and is illustrated in the accompanying photograph, which shows in perspective the front and one side of the case.

The leading features of this design consist in the ornamental lattice or scroll work which appears in the front board of the key-board projection and in the back board, in the ornamental rosettes which appear at the front board and at the end of the case, in the linear ornaments which appear on the music-desk, and in the ornamental outline and edge ornamentation of the sides of the key-board pro-

jection.

A is the front board of the case; B, the front of the key-board projection; C, the music-desk; D, the back board; E, the end of the case; F, the top, and G the base.

The front board A of the case has three panels *a b b*. The two side panels *b* are square and the central panel *a* is rectangular, having a greater width than height. The stiles and meeting stiles *c* bordering the panels are ornamented by vertical lines or grooves, as shown. The central panel *a* is without ornament. Each side panel is ornamented in its center by a square blazed rosette *d*, as shown.

The front of the key-board projection B has two narrow horizontal panels *e e*, each of ornamental open or lattice work. The lattice-work of each panel is made up of a plurality of inverted rings tangential with each other and with the horizontal margins of the panel, as shown. The inner periphery of each amulet is separated with quadrants by inwardly and radially extending tongues, as shown.

The music-desk C is ornamented as follows: The desk is divided into three sections *f g h*. The lower and intermediate sections (and likewise the upper and intermediate sections) are separated by two parallel horizontal lines extending across the desk, as shown. These two straight horizontal lines are connected by short vertical lines, which divide the space

between the horizontal lines into squares, as shown. Each square is ornamented, as shown, by a central mark. The lower section *f* is without ornament. The intermediate section *g* is ornamented by three groups of vertical lines, as shown. The upper section is ornamented by a stellated ornament in the center, two volutes near the ends, and two foliage ornaments between the volutes and the stellated ornament, as shown.

The back board D is ornamented along its entire length by a horizontal band *h'*, which is formed of two parallel series of straight horizontal lines, the spaces between the two series being divided at regular intervals into small squares by vertical lines. The back board is further ornamented on each side of the music-desk by a square panel *i* of ornamental open or lattice work. This lattice-work is composed of a central ring with four equally-distant internal projections or tongues, making a figure resembling a quarterfoil, four long narrow bands or fillets extending from the central ring to the centers of the four margins of the panel, and a series of short narrow bands or fillets of equal length extending radially from the ring, the spaces between the outer ends of the short fillets being filled with diamond-shaped pieces arranged in a circle concentric with the ring, all as shown. The lattice-work of the panel also forms ornaments in the corners simulating brackets or ancones, as shown.

Each end E of the case includes a vertical narrow rectangular panel *j*, extending from the base G to near the top, a square panel *k* at the top, and a front projection *ll*, which also constitutes the sides of the key-board projection. The end E of the case, near the center of the panel, is ornamented by two brackets *l*, having a fluted bar *m* between them, each bracket being ornamented at its center by horizontal lines and two fluted bands, as shown. The upper square panel *k* is ornamented by a square blazed rosette *d*, similar to the rosettes on the front board, as shown. Above the upper (and below the lower) rail of the panel *k* the end E is ornamented by straight lines, as shown.

The front projection *ll* of each end is sepa-

rated from the end panels *j* and *k* by a stile. The projection is characterized by its ornamental contour along its front edge. This front edge springs from the base in an engraved curve, which terminates just below and in front of the front board of the key-board projection *B*. From this point the edge extends vertically in a straight line above the key-board, and thence extends in an engraved 5 quadrant, terminating at the base of a pilaster *I* below the top *F* of the case. The projection *H* is ornamented at the center of the lower engraved curve by a die *l*', which is ornamented by recesses, as shown. The central and widest part of the projection is ornamented by three horizontal contiguous fluted bands *m*' *m*', which extend across the front 10 vertical edge of the projection *H*, as shown. The upper and lower of these bands are fluted 15 alike; but the intermediate band is fluted in a contrasting manner, as shown. The corners between the vertical portion of the front edge of the projection and the engraved curves thereof are ornamented with flutes, as 20 shown.
 The base *n* of the pilaster *G* and its capital *o* are each ornamented with flutes, as shown. The abacus *p* is of great proportional height and is ornamented in relief, as shown.
 The corners between the top *E* and the pilaster *G* are ornamented by brackets or ancones *J*, which are in turn ornamented by a 25 fan-like ornament resembling rays, as shown.
 The supporting-brackets *K* of the lamp- 30 mats *L* are ornamented by being of skeleton

shape, the stems of which the brackets are formed being wreathed or twisted, as shown.

I claim as my invention—

1. The design for an organ-case, as herein shown and described. 40
2. In an organ-case, the design for the ornamentation of the front board *A* thereof, as shown and described.
3. In an organ-case, the design for the ornamentation of the front *B* of the key-board projection thereof, as shown and described. 45
4. In an organ-case, the design for the ornamentation of the music-desk *C* thereof, as shown and described.
5. In an organ-case, the design for the ornamentation of the back board *D* thereof, as shown and described. 50
6. In an organ-case, the design for the ornamentation of the ends *E* thereof, as shown and described. 55
7. In an organ-case, the design for the ornamentation of the front projection *H* of the ends thereof, as shown and described.
8. In an organ-case, the design for the ornamentation of the corners between the top and ends thereof, consisting of the brackets or corbels *J*, as shown and described. 60

In witness whereof I have hereunto signed my name in the presence of two subscribing witnesses.

LEVI K. FULLER.
